UNITED STATES PATENT OFFICE.

OWEN OSBORNE, OF PHILADELPHIA, PENNSYLVANIA, ASSIGNOR TO OWEN OSBORNE INCORPORATED, OF PHILADELPHIA, PENNSYLVANIA, A CORPORATION OF PENNSYLVANIA.

METHOD OF PRODUCING SEMIPERMANENT MARKINGS ON SILK FABRICS.

Application filed July 18, 1924. Serial No. 726,723.

To all whom it may concern:

Be it known that I, OWEN OSBORNE, a citizen of the United States, residing in the city and county of Philadelphia and State of Pennsylvania, have invented a new and useful Method of Producing Semipermanent Markings on Silk Fabrics, of which the following is a specification.

My invention relates to a novel method of 10 producing a semi-permanent marking on textiles, particularly hosiery, and it relates more particularly to a method of embossing a name, legend or advertising symbol in a semi-permanent manner on the toe or other 15 portion of hosiery, particularly silk hosiery.

To the above ends my invention consists of a novel method of producing a semi-permanent marking, by embossing said marking in the fabric of the toe of a stocking, or the like by certain steps involving 20 moisture, heat and pressure.

My invention further consists of a novel method of embossing and marking on the toes of hosiery, consisting in subjecting the 25 surface of the fabric of said hosiery to the simultaneous action of moisture, heat and pressure over a pre-determined area as determined by the particular shape of the die employed, and for a pre-determined period 30 thereby producing a hardened glossy surface over or at the portions affected and a normal surface over the portions unaffected by the pressure.

For the purpose of illustrating my invention I have shown in the accompanying drawings forms thereof which are at present preferred by me, since the same have been found in practice to give satisfactory and reliable results, although it is to be understood that the various instrumentalities of 40 which my invention consists can be variously arranged and organized and that my invention is not limited to the precise arrangement and organization of the instrumentalities as herein shown and described.

Figure 1 represents a plan view of a stocking embossed by the novel method embodying my invention.

Figure 2 represents a plan view of a press 50 employed to carry out my invention.

Figure 3 represents a side elevation of the same.

Figure 4 represents on an enlarged scale a section on line 4-4 of Figure 2.

Figure 5 represents on an enlarged scale 55 a plan view of a stocking embossed in accordance with my invention.

Figure 6 represents a perspective view of the embossing die employed in carrying out 60 my invention.

Similar numerals of reference indicate corresponding parts in the figures.

Referring to the drawings:—

1 designates a stocking having a foot or toe portion 2 and a characteristic marking 65 3 thereon, embossed in a semi-permanent manner according to my invention.

In carrying out my invention the stocking 1 is placed upon a sheet of heavy paper or thin card board 4, and the die 5, with the 70 engraved surface thereof moistened with water, is superimposed upon the toe 2 thereof, and the paper 4 carrying the stocking or a plurality of stockings 1 with the dies 5 superimposed thereon, is placed between two 75 plates 6 and 7 of the press 8, as shown in Figure 4.

The plates 6 and 7 are hollow and are supplied with steam or other source of heat, through the piping 9 so that the plate 6 80 serves as a heated bed, and the plate 7 as a heated pressure plate. The two plates 6 and 7 are now brought together by means of any pressure mechanism such as shown in Figure 3 and the stocking and die is thus 85 held under pressure for a period of approximately three minutes, after which the pressure is relieved and the stockings and dies removed from the paper 4.

The impression thus produced on the 90 stocking is illustrated in Figure 5, wherein the letters 10 are depressed on a background 11, and are of the same appearance as the body of the fabric, while the depressed background portion 11 corresponding to the 95 smooth surface 12 of the die 5 has a hard glossy appearance, wherein the texture of the fabric is merged. In its entirety this gives the impression of the letters 10 being raised above the background 11. The die 100 5 may be made of any hard nonconducting material, preferably of a hard wood, such as maple, and the characteristic markings or letters 13 may be engraved into a smooth surface 12 thereof, as shown in Figure 6.

By my novel method of embossing silk stocking, I am enabled to produce any characteristic design, symbol marking or letter-

ing on the toe or any other part of the stocking, which will stand out very clearly, and will be of an unusually attractive appearance, in which no foreign ingredient or material is employed to effect said visible marking, and the marking thus produced can be readily erased by wetting, and the lettering will normally be erased when the stocking is first worn.

10 By my novel method I have produced moreover a semi-permanent marking on silk hosiery, without the aid of any foreign material or ingredients, and without in any way harming the fabric or decreasing the 15 original strength and luster of the fabric. The elements for simultaneously applying heat and pressure to the moistened die and stocking may be variously constructed. In Figures 2 and 3, I have shown a conveniently manipulated press, which has given excellent results in practice, wherein the heated bed or base member 6 has the guide posts which pass through holes in the ears 15 of the upper heated plate or heat chamber 7, the plates 6 and 7 being normally held apart by the springs 16. 17 designates upright lugs on the bed plate 6, in which the cam shaft 18 is mounted, carrying the cam 19, said shaft and cam being actuated by the 20 handle 20. The actuation of the handle 20 moves the upper heated member 7 towards the heated bed member 6, and upon releasing said handle, the springs 16 automatically move the member 7 upwardly 25 away from the bed 6.

It will now be apparent that I have devised a novel and useful method of producing semi-permanent markings on silk fabrics, which embodies the features of advantage enumerated as desirable in the 40

statement of the invention and the above description, and while I have in the present instance, shown and described a preferred embodiment thereof which will give in practice satisfactory and reliable results, it is 45 to be understood that the same is susceptible of modification in various particulars without departing from the spirit or scope of the invention or sacrificing any of its advantages.

Having thus described my invention what I claim as new and useful and desire to secure, by Letters Patent, is:—

1. The method of producing a semi-permanent marking on silk hosiery without the aid of any foreign ingredients, which consists in moistening the engraved surface of a die, placing said moistened surface against a stocking and lastly subjecting said assembled die and stocking to the simultaneous 60 action of heat and pressure.

2. The method of producing a semi-permanent marking on textile fabrics, which consists in superimposing said fabric on a heated bed, placing against said fabric a rigid die with a moistened working face, the latter being contiguous to said fabric and lastly applying heat and pressure for a predetermined period to the inoperative face of said die.

3. The method of producing a semi-permanent marking upon silk hosiery, which consists in moistening the engraved surface of a rigid, rectilinear die, superimposing said moistened die surface upon said hosiery, and lastly subjecting said assembled die and hosiery to the simultaneous action of heat and pressure.

OWEN OSBORNE.
